ANTHONY E. CARLSON, OF LOS ANGELES, CALIFORNIA

ROTARY BIT

Application filed September 7, 1926. Serial No. 133,836.

This invention relates to drill bits employed in the rotary system of drilling wells, and it relates particularly to a drill bit having revolving cutters.

5 In the drilling of oil wells by rotary system, a hole is sunk by means of a cutter secured at the lower end of a drill pipe. This drill pipe extends to the surface of the ground and is rotated by means of a rotary 10 table situated in the derrick of the well. As the rotary cutter is rotated, the bottom of the hole is cut away. There are two types of cutters commonly used in this system, the flat drill which includes fishtail and diamond- 15 point drills, and drills having rotating cutters such as disc, cone or cylinder cutters. My invention relates to rotary drills having rotating cutters.

It is an object of my invention to provide 20 a rotary drill bit of this character which cuts extremely fast. I accomplish this by providing the bit with cutters, certain of said cutters having circumferential teeth and certain of said cutters having axial teeth. 25 The engagement of these teeth with the bottom of the hole tends to checker or form projections thereat which readily splinter or crumble away as the bit is rotated.

It is another object of my invention to 30 provide a rotary bit of this character which will not form cores during drilling operations. A core is a formation which is formed and extends upwardly between the cutters of a bit as a hole is sunk. This core interferes 35 with the drilling of the hole by its engagement with the lower portion of the body of the bit between the cutters. When drilling through extremely hard formations, this core will not crumble away when it engages the 40 body of the bit and considerable interference to the drill is occasioned. This interference either greatly retards the drilling, or it deflects the drill bit to one side, thus causing a crooked hole to be drilled. In my invention 45 I arrange the cutters of my bit in such a position that one of said cutters operates over the center of the hole being drilled, thus eliminating formation of any core whatever.

It is also an object of my invention to 50 provide a drill bit of this character which is

superior to other bits, inasmuch as it is extremely simple in construction, has few parts, and is very rugged, so that it may endure great strains.

It is a further object of my invention to 55 provide a rotary disc bit of this character having a unique cutter support. The cutter support provided by my invention is preferably provided in an integral member adapted to be secured to a body of the bit. This integral member has a depending central wall, from which cutter supporting arms extend in different directions. The cutters of the bit are first placed upon the cutter supporting 60 arms and then the cutter support is installed in place in the body. The construction of the cutter supporting arms is such that they engage the body in such a manner as to lock the cutters in place. The salient advantages 65 of a construction of this character are that there are less parts to the bit; the parts are massive, and consequently very strong and various parts are very facile to install and remove.

It is also an object of my invention to 70 provide a rotary bit of this character in which it is practically impossible to lose any of the parts. During the operation of a present type of drill, the parts of the body carrying the cutters are sometimes worn away to the 75 extent that the cutters are lost. My bit is so constructed that it is impossible for the cutter supporting parts to wear in such a manner as to permit their being lost.

Other objects and the especial advantages 80 of my invention will be made evident in the following description.

Referring to the three sheets of drawings 85 in which I illustrate a preferred embodiment of my invention,

Fig. 1 is a diagrammatic view illustrating 90 the utility of my invention.

Fig. 2 is a vertical sectional view of a drill bit embodying the features of my invention.

Fig. 3 is a vertical sectional view through 95 the bit shown in Fig. 2, this view being taken substantially on the line 3-3 of Fig. 2.

Fig. 4 is a horizontal cross section taken through the cutter carrying arms and the cutters of my invention, this view being taken 100

substantially on a plane indicated by the lines 4—4 of Figs. 2 and 3.

Fig. 5 is a horizontal cross sectional view taken on a plane indicated by the line 5—5 of Fig. 3.

Fig. 6 is a view showing the novel form of bearing bushing employed in my invention, this view being taken on a plane as indicated by the line 6—6 of Fig. 4.

Fig. 7 is a vertical cross sectional view taken through the body of the bit of my invention.

Fig. 8 is a perspective view clearly illustrating the construction of cutter support provided by my invention.

With particular reference to Fig. 1, I show a rotary bit 11, which embodies the features of my invention, sinking a well 12. The rotary bit 11 is secured at the lower end of a drill pipe 13 which extends upwardly through the well 12 to the surface of the ground. On a derrick 14 of the well 12 is a rotary table 15 which engages the pipe, as shown, for the purpose of giving rotation thereto in a manner to rotate the rotary bit 11, thus sinking the well 12. A traveling block 17 is provided by which the drill bit 11 is fed downwardly as the well is drilled. Rotary mud is forced downwardly through the drill pipe 13 to the bit 11 by means of a pressure pump 18, which is connected to the upper end of the drill pipe 13 by means of a stand pipe 20, a hose 21 and a swivel head 22, this pressure pump 18 obtaining its supply of rotary mud from a sump 23 through a pipe 24.

The rotary bit 11 embodying the features of my invention is clearly shown in Figs. 2 to 8, inclusive, of the drawings. With particular reference to Figs. 2 and 3, the bit 11 is provided in the form of a body 24 to which is secured a cutter support 25. As clearly shown in Fig. 7, the body 24 has a threaded pin 26 which is adapted to thread into a box 27 of a tool joint 28, which tool joint as shown in Fig. 1 is attached at the lower end of the drill pipe 13. Opening from the bottom of the body 24 is a shoulder cavity 30, this cavity or bore having a cylindrical portion 31 and a cylindrical portion 32, between which a shoulder 33 is formed. Diametrically opposite legs 35 depend from the body 24. These legs 35, as shown in Fig. 7, have notches 37 which provide bearing faces 38. Diametrically opposing legs 40 also depend from the body 24, these legs being spaced at substantially ninety degrees with respect to the legs 35. The legs 40 have notches 41 which provide upper bearing faces 42.

The cutter support 25, as clearly shown in Fig. 8, has a shouldered portion 46 which is provided in the form of cooperating cylinders 47 and 48, between which there is provided a shoulder 49. As clearly shown in Figs. 2 and 3, the support is installed in the body 24 in such a manner that the cylinder 47

extends into the portion 31 of the cavity 30, the cylinder 48 extends into the portion 32 of the cavity 30, and the shoulder 49 of the support 25 engages with the shoulder 33 provided by the cavity 30. A securing bolt 50 extends through openings 51 in the body 24 and through an opening 52 in the support 25, thus securing the support 25 in the body 24. A central wall 53 depends from the shouldered portion 46. As clearly shown in Figs. 4 and 8, the central wall 53 rests in a plane slightly to one side of the axis of rotation of the bit, this central wall extending parallel with and to one side of a line A—A of Fig. 4, which line A—A passes through the axis of the bit. Angled cutter arms 54 extend outwardly from this central wall 53 in the direction of extension thereof, these angled cutter arms being square in cross section, as is evident from Fig. 8. The arms 54 extend outwardly in the same vertical plane but extend at angles relative to each other with respect to a horizontal plane. As is clearly evident in Fig. 4, the arms 54 are offset slightly with respect to the depending central wall 53 so as to extend centrally on the plane A—A, which extends through the axis of rotation of the bit. Straight cutter arms 56 extend from the depending central wall 53 substantially at right angles to the extension thereof. These straight cutter arms are square in cross section and extend in a plane B—B of Fig. 4, which plane extends through the axis of rotation of the bit, these arms 56 being in alignment in a vertical plane and also in a horizontal plane.

On each of the arms 54 and 56 bearing bushings 58 are placed. As clearly shown in Fig. 6, these bearing bushings have a rectangular opening 59, through which one of the arms 54 or 56 extends; therefore, the bearing bushings 58 are non-rotatable with respect to the arms 54 or 56. The bushings 58, however, have a cylindrical outer bearing face 60. On the bushings 58 of the arms 56 are placed cone cutters 63 and 64. The cone cutter 63 is provided with axial teeth, whereas the cone cutter 64 is provided with circumferential teeth.

Between the faces 62 of the central wall 53 and the inner ends of the cone cutters 63 and 64, I place wear plates 65. Between the legs 40 and the outer ends of the cone cutters 63 and 64 I place wear plates 66. The outer ends 67 of the arms 56, as clearly shown in Fig. 3, extend into notches 41 in the legs 40, and the upper faces thereof engage with the bearing faces 42 of the notches 41. On the bearing bushings 58 of the angled cutter arms 54, I place, as shown in Fig. 2, cylindrical cutters 69 and 70. The cutter 69 has circumferential teeth and the cutter 70 has axial teeth. Between the edges 71 of the central wall 53 and the inner ends of the cutters 69 and 70 I place wear plates 72, and between the legs 35 of the body 24 and the outer ends of the cutters 130

69 and 70 I place wear plates 73. As is evident from Fig. 2, the angularity of the cutter arms 54 disposes the cylindrical cutters 69 and 70 on angles also. The outer ends of the angled 5 arms 54 are flattened at 74 and extend into the notches 37 of the legs 35 so that the faces 74 of the arms 54 engage the bearing faces 38 provided by the notches 37.

The cone cutters 63 and 64 are arranged 10 fairly close together and may be considered as inner cutter members. The inner end of the cone cutter 63 extends over the center of the hole being drilled; that is, it extends over a point directly below the axis of rotation of 15 the bit. This is possible due to the offsetting of the depending wall 53 to one side of the axis A—A of Fig. 4. The purpose of this will be explained later. The cylindrical cutters 69 and 70 may be considered as outer cutters, due to the fact that they are spaced a 20 distance apart. By disposing these cutters at angles as shown, it is possible to extend the lower and outer cutting edges as indicated at 76 to a point protruding the exterior face 25 of the body 24, thus making it possible to cut the well 12 of a larger size than the body 24 so that the body may pass freely therein.

Rotary mud is supplied to the various cutters 63, 64, 69 and 70 through fluid passages 20 78 formed in the body 24 and fluid passages 79 formed in the support 25, there being a passage for each of these cutters, as is evident from Fig. 5. During the operation of the bit 11 in the well 12, rotary mud is forced by the 35 pressure pump 18 downwardly through the drill pipe 13, this rotary mud passing out of the passages 79 of the support 25, thus washing the teeth of the cutters and the surface against which the cutters are working. This 40 rotary mud flows upwardly and carries with it to the surface of the well cuttings produced by the bit.

The feature of providing cutters having axial and circumferential teeth is a very important consideration of my invention. As 45 the bit 11 rotates, the cutters 63 and 70 engage the surface against which they are cutting in such a manner as to cut radially extending grooves or recesses therein. The circumferential toothed cutters 64 and 69 engage the 50 bottom of the hole and produce circular grooves or recesses therein. It is evident that the combined cutting of the radial teeth and the circumferential teeth produces a checkered surface; that is, the bottom of the hole 55 is cut in such a manner that a multiplicity of pyramid-shaped projections extend therefrom. As the action of these cutters continues, the projections formed thereby readily 60 splinter and crumble away. The teeth of the cutters are never entirely embedded in the material being cut, due to the cross direction of cutting of the two sets of cutters. This arrangement makes the drilling, especially 65 through hard material, much quicker than

at present, and also reduces the wear on the cutters.

The cutter 63, as previously mentioned, extends to a point so that the inner end operates directly over the center of the hole. By this 70 provision there is no central projection or core formation which might interfere with the progress of the bit. This construction entirely prevents the forming of any cores 75 which might hinder and retard the drilling of a hole.

The ease with which the few parts of my bit may be assembled is also a prominent consideration of the invention. From the drawings it is evident that previous to the 80 installing of the support 25, the bearing bushings 58 and the cutters 63, 64, 69 and 70 are installed on cutter carrying arms 54 and 56. The support 25 is then installed in place as shown in Figs. 2 and 3, and the securing pin 85 50 is then extended into place as shown in Fig. 5. When the support 25 is thus installed, the ends of the cutter carrying arms 54 and 56 extend into the notches 37 and 41, respectively, the upper edges thereof engaging 90 with the bearing faces provided by the legs of the body 24. It will be seen that when the support 25 is in place, the legs 35 and 40 retain the cutters in their proper positions. Likewise, to remove or to replace the 95 cutters of the bit, it is conveniently done by removing the pin 50 which allows the removal of the disc support 25. When the disc support 25 has been separated from the body 24, it leaves the cutters free to be removed 100 from the ends of the arms 54 and 56.

In some of the present types of rotary bits, it often occurs that the body of these bits wears to the extent that certain of the cutter parts are lost. As is evidenced from the 105 drawings, before any part of my bit can be lost, it will be necessary for the entire body 24 to wear down a distance equal to the thickness of the legs 35 or 40. A wearing to this extent is absolutely impossible. My bit has 110 but very few parts which are very rugged and cheap to manufacture.

This is a continuation in part of my application entitled Rotary bit, filed December 27, 1924, Serial No. 758,376. 115

I claim as my invention:

1. In a drill bit of the class described, the combination of: a body; a cutter support secured to said body, said cutter support comprising a shouldered portion adapted for insertion into a shouldered cavity of said body, transversely projecting cutter carrying arms extending below said shouldered portion and angled relative to a horizontal plane, and 120 transversely projecting horizontal cutter carrying arms extending below said shouldered portion; cutters carried by said angled and said horizontal cutter carrying arms and means at the lower end of said body for en- 125 130

gaging at least one of said cutter carrying cutting arms.

2. A drill bit as defined in claim 1 in which the body is provided with relatively spaced depending legs, each engaging the outer end of one of said arms.

3. In a drill bit of the class described, the combination of: a body; a cutter support secured to said body, said cutter support comprising a shouldered portion adapted for insertion into a shouldered cavity of said body, transversely projecting cutter carrying arms extending below said shouldered portion and angled relative to a horizontal plane, and transversely projecting horizontal cutter carrying arms extending below said shouldered portion, said cutter carrying arms being square in cross section; bearing bushings carried by said cutter carrying arms, said bearing bushings having a square opening through which said arms extend and having a cylindrical external face; and cutters carried by said bearing bushings.

4. In a drill bit of the class described, the combination of: a body; supporting means carried by said body; inner conical cutters carried by said supporting means, said inner conical cutters being diametrically disposed in relation to said body, one of said inner cutters having axial teeth and the other of said inner cutters having circumferential teeth; and outer cylindrical cutters carried by said supporting means, said outer cutters being disposed on opposite sides of and arranged at right angles to said inner conical cutters, one of said outer cutters having axial teeth and the other of said outer cutters having circumferential teeth.

5. In a drill bit of the class described, the combination of: a body; supporting means carried by said body; inner conical cutters carried by said supporting means, said inner conical cutters being diametrically disposed in relation to said body, one of said inner cutters having axial teeth and the other of said inner cutters having circumferential teeth; and outer cylindrical cutters carried by said supporting means, said outer cutters being disposed on opposite sides of and arranged at right angles to said inner conical cutters, one of said outer cutters having axial teeth and the other of said outer cutters having circumferential teeth, one of said inner cutters having axial teeth extending adjacent to the axis of rotation of the bit.

6. A cutter support for a drill bit of the class described, comprising: a vertical shank having a depending portion provided with a plurality of relatively spaced transversely projecting cutter supporting arms adapted to extend into cutters mounted thereon and arranged in the form of a transversely disposed cross, said arms being square in cross section.

7. A cutter support for a drill bit adapted for insertion into a drill body, the whole to

be secured to a drill pipe, comprising: a vertical shank having a depending portion provided with a plurality of relatively spaced transversely projecting cutter supporting arms adapted to extend into cutters mounted thereon and arranged in the form of a transversely disposed cross, each alternate arm being disposed in a horizontal plane and each intermediate arm being disposed at an angle to a horizontal plane, said arms being polygonal in cross section.

8. In a drill bit of the class described, the combination of: a body having a bore extending upward from its lower end, said body being adapted to be secured to a drill pipe; a cutter support having a shank extending into said bore and a depending portion provided with transversely projecting horizontal cutter carrying arms and other transversely projecting arms angled relative to a horizontal plane; cutters carried by said arms; and means for securing said support to said body so as to maintain the same substantially within the bore.

9. In a drill bit of the class described, the combination of: a body having a bore extending upward from its lower end; a cutter support having a shank extending into said bore and a depending portion provided with transversely projecting horizontal cutter carrying arms and other transversely projecting arms angled relative to a horizontal plane; cutters carried by said arms; and means for securing said support to said body, said body having relatively spaced depending legs, each engaging one of the arms of said support.

10. In a drill bit of the class described, the combination of: a body having a bore extending upward from its lower end; a cutter support having a shank extending into said bore and a depending portion provided with transversely projecting horizontal cutter carrying arms and other transversely projecting arms angled relative to a horizontal plane, said arms being square in cross section; bearing bushings on said arms; cutters journaled on the respective bushings; and means for securing said support to said body.

11. A drill bit as defined in claim 10 in which the body is provided with relatively spaced depending legs, each vertically notched at its lower end, to receive the outer end of one of the arms of said support.

12. In a drill bit of the class described, the combination of: a body having a bore extending upward from its lower end; said body being adapted to be secured to a drill pipe, a cutter support having a shank extending into said bore and a depending portion provided with transversely projecting horizontal cutter carrying arms and other transversely projecting arms angled relative to a horizontal plane; bearing bushings non-rotatably mounted on said arms; cutters journaled on the respective bushings; means for

securing said support to said body and means carried by said body for engaging said arms.

13. A drill bit as defined in claim 12 in which the body is provided with relatively spaced depending legs, each vertically notched at its lower end, to receive the outer end of one of the arms of said support.

14. In a drill bit of the class described, the combination of: a body; a cutter support secured to said body, said cutter support comprising a shouldered portion adapted for insertion into a shouldered cavity of said body, transversely projecting cutter carrying arms extending below said shouldered portion and angled relative to a horizontal plane, and transversely projecting horizontal cutter carrying arms extending below said shouldered portion; bearing bushings non-rotatably mounted on said arms; cutters carried by said bearing bushings and means carried by said body for engaging said arms.

15. A body for a drill bit of the class described having an axial bore extending upward from its lower end and provided with relatively spaced depending legs disposed around said bore, the lower ends of said legs each being provided with a vertically disposed notch, said bore and said notches being adapted to receive a cutter supporting means, the inner surfaces of an opposite pair of said legs being vertically disposed and relatively parallel, and the inner surfaces of another pair of said legs diverging downward and outward.

35 16. In a cutter support for a drill bit of the class described, the combination of: a plurality of pairs of rotary cutter supporting arms, the arms of each pair being disposed on opposite sides of the axis of the bit from each other; and an eccentric web connecting the inner ends of said arms.

17. A combination as in claim 16 in which said arms are disposed to support cutters so that the axes of rotation of said cutters intersect the axis of the bit.

45 18. A combination as in claim 16 in which the inner end of one of said arms extends relatively close to the axis of the bit so that a cutter mounted on said arm cuts closer to the center of the hole than any of the cutters mounted on the other of said arms.

19. In a drill bit a cutter assembly comprising: a cutter support; two primary arms projecting from the sides of said cutter support; two secondary arms projecting from the ends of said cutter support; a body having a bore extending upwardly from its lower end, means for securing said cutter support to said body, and maintaining it substantially within the bore, and cutters mounted on all said arms in operative position.

20. In a drill bit of the class described, the combination of: a body having a bore extending upwardly from its lower end, a cutter support having a shank extending into

said bore and a depending portion provided with transversely projecting horizontal cutter carrying arms and other transversely projecting arms angled relative to a horizontal plane; cutters carried by said arms, means for securing said support to said body, and means carried by said body for engaging said arms.

In testimony whereof, I have hereunto set my hand at Los Angeles, California, this 30th day of August, 1926.

ANTHONY E. CARLSON.
